US00D910392S

(12) **United States Design Patent** (10) **Patent No.:** **US D910,392 S**
(45) **Date of Patent:** **** Feb. 16, 2021**

(54) **SPANNER**

(71) Applicant: **Hong Ann Tool Industries Co., Ltd.**,
Taichung (TW)

(72) Inventor: **Cheng-Wei Su**, Taichung (TW)

(73) Assignee: **Hong Ann Tool Industries Co., Ltd.**,
Taichung (TW)

(**) Term: **15 Years**

(21) Appl. No.: **29/693,410**

(22) Filed: **Jun. 3, 2019**

(51) LOC (13) Cl. **08-05**

(52) U.S. Cl.

USPC **D8/27; D8/28**

CLAIM

The ornamental design for a spanner, as shown and described.

DESCRIPTION

FIG. 1 is a perspective view of a spanner showing my new design;

FIG. 2 is a front view thereof;

FIG. 3 is a left view thereof;

FIG. 4 is a right view thereof;

FIG. 5 is a top view thereof; and,

FIG. 6 is a bottom view thereof.

The broken lines shown are included for the purpose of illustrating portions of the spanner that form no part of the claimed design.

1 Claim, 5 Drawing Sheets
